UNITED STATES PATENT OFFICE.

BENJAMIN F. MCGUINNESS, OF GRAFTON, MASSACHUSETTS, ASSIGNOR TO CROMPTON & KNOWLES LOOM WORKS, OF WORCESTER, MASSACHUSETTS, A CORPORATION OF MASSACHUSETTS.

HARNESS CAM LEVER AND ROLL.

Application filed January 2, 1924. Serial No. 683,969.

To all whom it may concern:

Be it known that I, BENJAMIN F. MCGUINNESS, a citizen of the United States, residing at Grafton, in the county of Worcester and State of Massachusetts, have invented a new and useful Harness Cam Lever and Roll, of which the following is a specification.

This invention relates to harness mechanism for looms and more particularly to the construction of the levers and cam rolls such as are employed on so-called cam harness motions.

In harness motions of the type to which this invention relates it is customary to have a group of relatively thin cams fastened to a driven shaft and a corresponding group of harness levers, one for each cam, the levers being connected to the harness frames. When a motion of this type is applied to looms for weaving very heavy fabrics it is found that the rolls which cooperate with the cams are subjected to such heavy strain as to break the studs upon which they are mounted. Accordingly, it is the principal object of my invention to provide an improved mounting for the rolls so that the same may be used for weaving heavy fabrics without undue breakage.

A further object of my invention is to provide a harness lever with a roll bearing part of which is formed directly on the lever and the remainder of which is provided by means of a stud.

With these and other objects in view which will appear as the description proceeds, my invention resides in the combination and arrangement of parts hereinafter described and set forth in the claims.

In the drawings, wherein I have shown a convenient form of the invention,

Fig. 1 is a top plan view of a cam harness motion to which my invention may be applied,

Fig. 2 is an end elevation of the structure shown in Fig. 1, and

Fig. 3 is an enlarged section through the harness lever, roll, stud and portion of the associated cam.

Referring to the drawings it will be seen that the loom side 10 has secured thereto and extending therefrom a frame 11 having cross girts 12 on which are mounted bearings 13. Shaft 14 is received by the bear-

ings 13 and is driven by means of a gear 15 operated from any source of power (not shown). A group of cams 16 is mounted on the shaft 14 and each of said cams is arranged to move with the shaft as the gear 15 rotates.

Stands 17 are mounted on the frame 11 and support shaft 18 which gives bearing to the hubs 19 of the cam levers 20. The opposite ends of the levers are provided with connectors 21 which are operatively connected to the harness frames (not shown).

As shown in Fig. 2 the cams are provided with tracks 22 which cooperate with the rolls 30 carried by the levers. The roll operating faces of the cams are arranged so as to move the levers and their harness frames in proper sequence to operate the harness to produce any predetermined weave, as is customary in this type of motion.

My invention has more particular reference to the construction of the lever and roll and by referring to Fig. 3 it will be seen that the lever 20, which may be taken as representative of all the levers shown in Fig. 1, is provided with a boss 31 extending laterally therefrom and through which passes the shank of a stud 32. The stud is provided with an enlarged bearing portion 33 which is of slightly greater diameter than the diameter of the boss 31. The roll 30 is provided with a bearing surface 34 to cooperate with the bearing surface 33 of the stud and also is provided with a second bearing surface 35 of somewhat less diameter than the surface 34 to cooperate with the boss 31. The cam track 22 is preferably defined by means of flanges 36 which have tapering walls 37 and the outer bearing surface of the roll 30 is crowned as indicated at 38 so that the driving contact between the flanges 36 and the roll 30 is located substantially in line with the enlarged portion 33 of the stud 32.

It is found when such a construction as disclosed herein is employed that it is possible to use a stud the shank of which is of considerably greater length and diameter than the thickness of the lever to which it is fastened. Also, because of the difference in the diameters of bearings 34 and 35 the portion 33 of the stud serves to retain

the roll and prevent accidental loss thereof. It will be further noted that although the shank of the stud is considerably longer than the thickness of the lever the roll is nevertheless provided with a bearing the length of which is substantially equal to the distance between the adjacent faces of the cam and lever.

Having thus described my invention it will be apparent that changes and modifications may be made therein by those skilled in the art without departing from the spirit and scope of the invention and I do not wish to be otherwise limited to the details herein disclosed, but what I claim is:

1. A loom harness lever having a boss extending laterally therefrom and provided with an external bearing surface, a stud extending through and beyond said boss and having a bearing surface of larger diameter than the diameter of the bearing surface of the boss, and a roll having internal bearing surfaces of diameters substantially equal to the diameters of the bearing surface of the boss and bearing portions of the stud.
2. In a harness lever, a roll rotatably mounted with respect thereto, said roll having internal bearing portions of different di-

ameters, a boss formed on the lever and having an external bearing surface to contact with the roll bearing surface of lesser diameter, a stud passing through the boss and held rigidly to the lever, and a bearing portion formed on the outer end of the stud of larger diameter than the diameter of the boss and in contact with the internal bearing of the roll of larger diameter.

3. In a cam harness motion, a cam having flanges formed with tapered inner surfaces, a roll having a crowned cam engaging face in engagement with said flanges, a cam lever, a boss on said lever having an external bearing surface, a stud passing through said boss and lever and secured to said lever and having a bearing surface of larger diameter than the diameter of the boss and internal bearing surfaces formed on the roll to engage said boss and said bearing surface of the stud, said roll having bearing contact with the tapered portion of the flanges which are most remote from the lever and in substantial alignment with the bearing surface of said stud.

In testimony whereof I have hereunto affixed my signature.

BENJAMIN F. McGUINNESS.
